UNITED STATES PATENT OFFICE.

WILLIAM B. MOORE, OF ORMAND, PENNSYLVANIA.

STEAM-BOILER CLEANER.

SPECIFICATION forming part of Letters Patent No. 375,648, dated December 27, 1887.

Application filed September 24, 1887. Serial No. 250,596. (No model.)

To all whom it may concern:

Be it known that I, WILLIAM B. MOORE, a citizen of the United States, residing at Ormand, in the county of Fayette and State of Pennsylvania, have invented certain new and useful Improvements in Steam-Boiler Cleaners; and I do declare the following to be a full, clear, and exact description of the invention, such as will enable others skilled in the art to 5 which it appertains to make and use the same, reference being had to the accompanying drawings, and to the letters and figures of reference marked thereon, which form a part of this specification.

15 My invention relates to a blow-off device for steam-boilers; and it consists of the peculiar construction and combination of devices, that will be hereinafter fully described, and particularly pointed out in the claims.

20 It is well known to engineers and boiler-attendants that sediment and impurities accumulate and float on the surface of the water, and that impurities and sediment pass or escape only through the gage-cock that is on the 25 water-line.

30 The object of my invention is to provide a blow-off device which is adapted for use on portable and stationary steam-boilers and which is so constructed and arranged that the 35 impurities and sediment which float on the surface of the water can be readily drawn from the boiler. This object I accomplish by a single device, which is simple in construction and reliable and efficient in operation.

35 In the accompanying drawings, Figure 1 is a vertical sectional view taken longitudinally through a steam-boiler; and Fig. 2 is a horizontal sectional view on the line $\alpha\alpha$ of Fig. 1, showing the blow-off device adjusted to a horizontal position for drawing off the sediment 40 on the surface of the water. Fig. 3 is an enlarged view of the bushing D and handle H.

Referring to the drawings, in which like letters of reference denote corresponding parts 45 in all the figures, A designates an ordinary steam-boiler, which in the present instance corresponds to the boiler of a portable steam-engine, which has the usual fire-box, B, and the flues C. I would have it understood, however, that my invention can be used on stationary steam-boilers as well as on portable

steam-boilers. In either end of the boiler, or at any other suitable point at either side of the boiler on the water-line therein, I secure, in any suitable manner, a stuffing-box, D, of 55 any preferred pattern, and this stuffing-box has the usual central opening or passage through which is passed a horizontal axially-rotating tube or pipe, E. This axially-turning pipe E is of such a length that its inner 60 end enters and communicates with the interior of the boiler above the crown sheet of the firebox therein, and the outer end of the pipe extends or projects beyond the boiler for a suitable distance. The extreme outer end of the 65 axially-turning pipe is provided with an angular nozzle, e, which normally assumes a vertical position when the pipe is at rest and out of use, the nozzle being of suitable length and serving to conduct the steam, water, gases, 70 and other impurities from the boiler. The inner end of this pipe E is provided with an angular or elbow arm or bend, F, which communicates with the horizontal portion of the pipe and is disposed at any suitable angle 75 thereto, preferably a right angle, and the outer extremity of this angular arm or bend has a flaring mouth or nozzle, f, arranged at right angles to itself, this flaring mouth extending in substantially the same horizontal direction as 80 the pipe E. The axially-turning pipe or tube E is provided with a valve, G, at a point between the nozzle at the outer end thereof and the point where it enters the bushing. This valve is of the ordinary pattern and is normally closed to cut off the escape of the steam, 85 gases, &c., from the boiler.

The operation of my invention is obvious. The tube or pipe E normally assumes a position so that the inner angular or elbow arm or 90 bend, F, thereof lies substantially in the plane of the horizontal axis of the pipe, or the elbow-arm may extend above the water-line and into the steam-space of the boiler, and the valve G is closed to prevent the egress of the steam, 95 &c. If it is desired to draw off the floating impurities or accumulated sediment on the surface of the water, the pipe or tube E is turned or rotated partially until the open flaring mouth thereof assumes a position on the 100 plane of the water-line of the boiler, the water and the impurities suspended therein or float-

ing on the surface thereof flowing freely into and through the pipe E. The pipe is rotated slowly by the attendant as the water in the boiler falls, so that the water will enter the 5 same at all times until it falls on or below the level of the crown sheet of the fire-box. To prevent the water in the axially-turning pipe or tube E from freezing, it is only necessary to turn the pipe until the arm F assumes a 10 vertical position and the nozzle e a horizontal or an inclined position, and then open the valve to permit the water to flow out of the pipe E and the nozzle e thereof.

From the foregoing description it will be 15 seen that by the use of the axially-turning valved pipe or tube located at or near the water-line of the boiler I am enabled to provide a simple and inexpensive device, which serves efficiently to draw off both the gaseous 20 and liquid or semi-fluid impurities that may accumulate in the boiler.

It will be understood that my invention is 25 to be used for drawing off the sediment or impurities that may accumulate on the surface of the water.

Any suitable contrivance may be employed 30 for turning or rotating the pipe or tube E, which device is to be located outside of the boiler and within convenient reach of the attendant. I prefer to employ a handle, H, which is made of wood or other non-conductor of heat and is rigidly fixed or secured to a shank, g, that is formed with a ring or sleeve, h, which is fitted over the nozzle e of the pipe 35 or tube E, said sleeve or ring being clamped to the nozzle at any suitable point by means of a binding-screw, h', which works in a threaded aperture in the sleeve or ring and bears against the nozzle, as shown.

40 Having thus fully described my invention, what I claim as new, and desire to secure by Letters Patent, is—

1. A blow-off device for steam-boilers, consisting of an axially-turning imperforate tube or pipe, E, passing through the boiler-shell at 45 or near the water-line thereof, an angular arm, F, fixed to the inner end of the tube or pipe and having at its free end a right-angled mouth, f, and a valve, G, fitted transversely in the tube or pipe at a point outside of the boiler-shell, substantially as described, for the purpose set forth.

2. The combination of a bushing, D, fixed in the boiler-shell at or near the water-line, an imperforate tube or pipe, E, fitted in the bushing and capable of turning freely on its axis therein, an angular arm or tube, F, fixed to the inner extremity of the pipe or tube and having a right-angled flaring mouth, f, extending therefrom in the same direction as the 60 tube or pipe E, and a valve, G, fitted transversely in the tube or pipe E at a point beyond the bushing, as and for the purpose described.

3. A blow-off device for steam-boilers, consisting of an imperforate axially-turning tube or pipe, E, having a depending nozzle, e, at its outer end, a bushing through which the pipe passes, an angular arm or tube, F, fixed to the inner end of the tube or pipe and having a 70 right-angled flaring mouth, a valve, G, fitted transversely in the tube or pipe at a point beyond the bushing, and a handle, H, provided with a sleeve which is fitted over the nozzle e, and with a set-screw for clamping the handle 75 and sleeve to the nozzle, as and for the purpose described.

In testimony whereof I affix my signature in presence of two witnesses.

W. B. MOORE.
